FIRE EXTINGUISHING APPARATUS

Henri Charles Laengel, Paris, France, assignor to
Societe Anonyme Assuro, Paris, FranceApplication June 15, 1929, Serial No. 371,215, and
in France June 28, 1928

2 Claims. (Cl. 169—9)

The present invention relates to a fire extinguishing apparatus which may be actuated automatically by the effect of the flames, or may be operated by distant control. For this purpose, 5 the plant consists of tightly closed tanks containing the fire-extinguishing liquid and connected to discharge pipes as well as to closed vessels containing gas under pressure. The opening of the said vessels, which permits the gas to enter 10 the tanks in order to expel the liquid therefrom, is effected automatically or by positive control.

A distributing device is connected with said tanks and is used to circulate the liquid from the different tanks to a common point of discharge.

15 The accompanying drawings show by way of example a plant as applied to the engines of aeroplanes or like aircraft, but it is obvious that the apparatus may be employed in stationary plants, for instance factories and the like.

20 Fig. 1 is a diagrammatic view of the general plant and for fire extinguishing purposes.

Figs. 2 and 3 show the apparatus for the control of the supply of gas under pressure, in the inoperative and the operative position, respectively.

25 Fig. 4 shows the tanks containing the fire extinguishing liquid as well as the distributing device.

Fig. 4a shows diagrammatically the distributing device.

30 Fig. 5 is a side view of the said device.

As above mentioned, the fire protecting system according to the invention comprises a plurality of vessels or tanks 1 which may be distinct or may be formed by partitioning a common casing 2, thus providing juxtaposed chambers. Each tank or chamber is provided with two tubular conduits, one of which, 3, is open at the top and also leads into the space above the fire extinguishing liquid contained in the tank; the other 40 conduit 4 is connected with an immersed tube 5 and extends to the bottom of the tank. When used upon aeroplanes, in view of the variations in the position of the tanks 1, which may even be inverted due to the reversal of the aeroplane, 45 the tube 5 is made flexible and is provided at the lower end with a strainer 6 which has the shape of a hollow sphere provided with a number of small holes. The strainer 6 is connected with a weight 7 made of lead or the like. In this manner 50 the strainer 6 will be always immersed to the bottom of the liquid, irrespectively of the position of the tank. In this case the conduits 3 and 4 are closed by disks 41 and 42 respectively which will burst under the pressure of the gas or liquid, 55 when the apparatus is in operation.

The disks 41 and 42 are used to prevent the liquid from escaping out of the tanks under normal pressure, even when these tanks are turned upside down, which can easily happen if the device is installed on board of an aeroplane.

60 The conduits 3 which open into the space above the liquid are each connected to a respective apparatus containing gas under pressure, and consisting of a cylinder 8 closed at one end by a screw cap 9.

65 At the other end of the cylinder is mounted a cover 10 protecting the inflammable cap 11 against shocks, and also a bottom piece 12 which is bored axially in order to guide the push-piece 13. At one end of the latter is a groove 14 adapted for the insertion of the bent ends of a fastening spring strip 15 which is secured at its middle part to a block 16 into which the end of the said push-piece may be inserted. The said block 16 is mounted on the bottom piece 12, and lateral 70 openings are provided for the movement of the ends of the spring 15 and for their engagement with the said groove of the push-piece. The branches of said spring are held against the outer face of the block 16 by the insertion of the block 16 and spring into the said inflammable cap 11. On the other hand, the cap 11 is held in place by friction by means of the spring 15.

75 To a lug at one side of the bottom piece 12 is pivoted a fork 17 having branches which may act upon the said cap 11, thus driving down the latter and releasing the spring 15. On the other side of the pivoting axle, the fork carries an arm to which is secured the end of a cable 18 pertaining to a flexible power transmission device.

80 The arm of the said fork as well as the corresponding part of the cable 18 are contained in a tube 19 secured to the cylinder 8 and having an axis which is parallel to the axis of this latter.

85 The upper end of said tube 19 is traversed by the said cable 18 and may form a support for said flexible power transmission device.

90 The push-piece 13 is provided, within the cylinder 8, with a shoulder 20 carrying at the top an annular groove for the insertion of a packing member 21. A spring 22 surrounds the push-piece and bears at the top against the said shoulder and at the bottom against the lower end of a socket 23 resting on the bottom 12 of the cylinder 8 and serving as an abutment for a socket 24, recessed at 25 and provided at the top with packing 26 cooperating with the neck of the bottle 27 containing the gas under pressure.

95 A side coupling 28 connects the said recess or chamber 25 to the corresponding pipe leading to 100

105 110

the conduit 3 of one of the respective tanks 1. A rod or shank 29 on the end of the push-piece 13 extends into the said chamber 25, said shank being held against rotation, for instance by a longitudinal groove in the said shank, cooperating with a stud mounted in the socket 25. Said shank 29 is adapted to engage the valve disk 30 which closes the gas bottle 27.

In the inoperative position, the parts are arranged as shown in Fig. 2. A gas bottle 27 is disposed in the cylinder 3, and its neck is pressed against the packing 26 by screwing down the cap 9. The push-piece 13 has been driven down, thus compressing the spring 22. The groove 14 coincides with the apertures permitting the insertion of the ends of the fastening spring strip 15. The push-piece 13 has been held fast by the insertion of the inflammable cap 11, and the cap brings the branches of the spring strip 15 against the block 16 and also engages the bent ends of the spring in the groove 14. In this manner, the apparatus is ready for use.

The said apparatus may be operated in two different ways, either by the burning of the said cap 11, or by driving it out by means of the said power transmission device comprising the flexible cable 18. In both cases, when the said cap ceases to hold the branches of the spring strip, these latter will separate, thus releasing their bent parts from the groove 14 of the push-piece 13, and as this piece is no longer held, it will be moved by its spring 22, so that the shank 29 makes contact with the valve 30 of the bottle 27, while at the same time the packing 21 comes against the corresponding seat on the socket 24. The gas under pressure escapes from the bottle and flows through the coupling 28 and the corresponding pipe, thus acting upon the liquid in the tank 1 after bursting the closing disk 41. The liquid is driven by the pressure through the strainer 6 into the tube 5, thus bursting the closing disk 42 and issuing through the discharge conduit 4.

The functioning will be the same, if the push-piece 13 acts by percussion instead of by opening the valve 30 which closes the gas bottle. In practice, the apparatus 8 comprises no screws, bolts or soldered parts. It can be readily taken apart by the use of a wrench.

All of the pipes leading from the tanks 1 containing the liquid may pass through a distributing device which is disposed between the said tanks and the pipes leading to the different points at which a fire may occur, the corresponding apparatus 8 being obviously situated at these points. The said distributing device is adapted to connect the tanks 1 to the pipes 4' which they are to normally protect, or to pipes 4' leading to other points on the premises. In this manner it is possible to use the contents of several tanks 1 against a fire which breaks out a second time at a given point.

The illustrated device comprises three tanks which contain the liquid and three apparatus for the compressed gas for the three points which are to be protected. The three conduits 4 for the liquid are connected with the tanks and at their opposite ends with the connecting pieces 31a, 31b and 31c respectively (Fig. 4a) attached to the lower part of the body 32 of a distributing valve. Three discharge members 33a, 33b and 33c (Fig. 4a) are situated on the upper part of the body 32 diametrically opposite the delivery members 31a, 31b and 31c, and are connected by conduits 4' with the points to be protected (Fig. 1). A plug 32' which can be turned by means of a

handle 34 is carried by the body 32. The handle 34 carries a stop-key 35 actuated by a spring 43, so that it can be locked by means of grooves provided on the surface of the body 32. The plug 32' comprises three parallel channels 42a, 42b, and 42c, the axis of the middle channel 42b being a diameter (Fig. 4a). When the plug 32' is in its middle position shown in Fig. 4a, the delivery member 31a is connected with the discharge member 33a, the member 31b with the discharge 85 33b and the member 31c with the discharge 33c. If for instance, the plug is rotated clockwise for about 45°, the middle channel 42b connects the delivery member 31c with the discharge member 33a, while the four other members 31a, 31b, 33b, 90 33c are not interconnected. Thus the right tank may be utilized for the left point to be protected, and vice versa.

Three levers 36 (Fig. 4) are mounted on the upper part of the distributing device and are used for pulling the flexible cables 18 which open compressed gas containers (Figs. 2 and 3). The levers 36 are mounted on pivots 43 situated in abutments 44 connected with the body 32 of the distributing valve. A lock 37 may be moved in front of the levers 36, said movement being limited by two screws 39 screwed into the body 32 and passing through horizontal slots 38 of the lock 37. The member 37 is moved by the handle 34 having an abutment 45 projecting into a vertical slot 46 of the member 37, which is of such dimensions that in its middle position it still allows the side levers 36 to move freely. An opening 40 is situated in the middle of the member 37, so that the middle lever 36 can also move 110 freely.

It will be seen from the above that when the plug 32' and the member 37 are in their middle position, each tank is connected with the corresponding point to be protected, and each lever 36 115 can be moved forwards so that it can pull the cable 18 and open the corresponding compressed gas container.

When the plug 32' is moved clockwise the supply member 31c is connected with the discharge member 33a the supply members 31a and 31b not being connected, as has been mentioned already. At the same time, the member 37 is moved to the right and locks the right hand lever 36 and the middle lever 36. Only the left lever 36 remains 125 free, so that by means of said lever compressed gas can be sent to the tank connected with the delivery member 31c. By means of this arrangement wrong manipulations can be easily avoided.

I claim:

1. In a fire protection system having a tank containing a fire extinguishing liquid, a pressure releasing device adjacent a location to be protected and responsive to a conflagration of said location, said device comprising a container containing a fluid under pressure and communicating with said tank, a valve situated in an opening formed in said container, means in contact with said valve for actuating the same, said means comprising a movable member and a spring pressing against said member; a fastening spring surrounding one end of said movable member, a removable inflammable cap surrounding the fastening spring and pressing it against said movable member for holding the same, and remotely controlled means adapted to come in contact with said inflammable cap for removing the same.

2. A fire protection system comprising in combination, a plurality of tanks, a distributing device, conduits connecting said distributing device 150

with said tanks, distributing pipes connected with said distributing device and leading from said distributing device to the various points to be protected, said distributing device comprising a rotatable plug having passages extending through said plug, each one of said passages being adapted to place a separate tank in communication with a separate distributing pipe at the normal position of said plug; a plurality of pressure releasing devices, each one of said pressure releasing devices being situated adjacent to a separate point to be protected and communicating with a separate tank, said pressure releasing devices being responsive to conflagrations at their particular locations, means connected with said plug for rotating the same, one of said passages being adapted after a rotation of said plug to place one of said tanks in communication with a distributing pipe which is different from the distributing
